UNITED STATES PATENT OFFICE.

ELLIS F. STENMAN, OF WORCESTER, MASSACHUSETTS.

SKIRT-MEASURING DEVICE.

No. 927,819.

Specification of Letters Patent.

Patented July 13, 1909.

Application filed April 4, 1908. Serial No. 425,290.

To all whom it may concern:

Be it known that I, ELLIS F. STENMAN, a citizen of the United States, residing at Worcester, in the county of Worcester and 5 Commonwealth of Massachusetts, have invented certain new and useful Improvements in Skirt-Measuring Devices; and I do hereby declare that the following is a full, clear, and exact description of the same, reference being had to the accompanying drawings, and to the characters of reference marked thereon, which form a part of this specification.

The principal object of the present invention is to provide a simple, novel and accurate device for determining the proper position of the lower edges of skirts, said device being readily adjustable and being formed of parts that can be cheaply manufactured and put together, the device dispensing with 20 all slots, bolts and projecting nuts.

In the accompanying drawings:—Figure 1 is a plan view of the device; Fig. 2 is a sectional view on the line 2—2 of Fig. 1; Fig. 3 is a front elevation of a portion of 25 the guide ring and one of the standards with its holding device; Fig. 4 is a side elevation of one of the standards; Fig. 5 is a rear elevation.

A guide ring 1 is provided, which is made 30 from spring steel or other suitable material, the ends thereof being overlapped and terminating in hooks 2.

Two holding clips are employed, each of 35 which is formed of a single wire having its central portion bent into a compression ring 3, the terminal portions being crossed, as shown at 4, and being disposed in parallel relation, forming jaws 5. One of these jaws is engaged with each side of the body of the 40 ring.

A plurality of standards or legs 6 are provided, four being shown, though any suitable number may be used. These legs or standards have off-set feet 7 at their lower 45 ends and they are arranged transversely of the ring 1. Their outer sides have suitable vertically arranged scales. They are firmly held against the ring and against movement on said ring by clips, each clip being formed 50 of a single wire having vertical cross-bars 8 arranged across one side of the ring, the ends of these cross-bars being connected by other cross-bars 9 that are arranged against the

opposite side of the standard. As shown in Fig. 5, the cross-bars 9 have their central 55 portions inset toward each other, as shown at 10.

With this construction the ring can be expanded or contracted as desired by compressing the rings 3 and then moving the 60 clips along the body of the ring, when the rings 3 are compressed. The guide ring is maintained at a fixed diameter by the frictional bearing of the jaws 5. In like manner, the ring 1 can be supported at any suitable height desired by sliding it upon the legs or standards 6, and wherever it is left, there it will remain. It will be evident, therefore, to any one skilled in the art that the device will constitute an accurate gage 70 for the purpose outlined, and the parts which form the same are simple and can be easily manufactured. Further than this, there are no slots, bolts or nuts which would add to the expense.

Having thus described my invention, what I claim as new and desire to secure by Letters Patent, is:—

1. A skirt measure or gaging device comprising a ring having slidably overlapped 80 ends, a holding clip carried by each end and movable therewith and comprising jaws, one of which is secured to and moves with one end, the other jaw being slidably engaged with the body of the ring, a spring compression device connecting the jaws, and means for supporting the ring.

2. A skirt measure or gaging device comprising a ring having slidably overlapped ends terminating in hooks, a holding clip 90 for each end comprising a single wire having its central portion formed into a compression ring and having its end portions crossed and forming jaws, one of which is engaged within one of the terminal hooks, 95 the other being slidably engaged with the body of the ring, and means for supporting the ring.

3. A skirt measure or gaging device comprising a guide ring, supporting standards 100 therefor arranged transversely of the ring, and clips having cross-bars that extend across and frictionally engage the ring, and other cross-bars connecting the first-named cross-bars and extending across and frictionally engaging the standards.

4. A skirt measure or gaging device comprising a guide ring, supporting standards for the guide ring arranged transversely of the same, clips each formed of a wire and comprising cross-bars that extend across and frictionally engage one side of the ring, and other cross-bars connecting the ends of the first-named cross-bars and extending across

the opposite side of a standard, the latter cross-bars having their central portions bent 10 toward each other in line with the ring.
